UNITED STATES PATENT OFFICE.

THOMAS J. YATES, OF SALEM, MASSACHUSETTS, ASSIGNOR TO YATES MACHINE COMPANY, OF SALEM, MASSACHUSETTS, A CORPORATION OF MASSACHUSETTS.

VALVE MECHANISM FOR WASHING-MACHINES.

1,185,567.

Specification of Letters Patent.

Patented May 30, 1916.

Application filed April 30, 1914. Serial No. 835,556.

To all whom it may concern:

Be it known that I, THOMAS J. YATES, a citizen of the United States, residing at Salem, county of Essex, State of Massachusetts, have invented an Improvement in Valve Mechanism for Washing-Machines, of which the following description, in connection with the accompanying drawing, is a specification, like characters on the drawing representing like parts.

This invention relates to valve mechanism particularly adapted to control the supply of hot and cold water to washing machines so that the water may be introduced into the washing receptacle in a regulated manner and shut off automatically when the level of the liquid in the receptacle reaches a predetermined point.

The principal object of the invention is the production of a simplified means for independently locking valves in the supply pipes in any desired open position, together with an instrumentality to unlock the valves and permit the closure thereof when the liquid reaches the predetermined level in the receptacle.

The valves used in connection with this invention may be of the character disclosed in my prior Patent No. 964,833 granted July 19, 1910 or of any other suitable type, as the present invention relates to the means for locking said valves in open position and the means for releasing the same.

The novel features of my invention will be more fully disclosed in the following specification and the annexed drawing and will be pointed out in the subjoined claims.

Figure 1 is a side elevation of the means for controlling the valves, showing one of the valves depressed and the valve releasing and closing mechanism located in position to permit the flow of water through that valve into the receptacle, Fig. 2 is a transverse sectional view on the line 2—2 Fig. 1, Fig. 3 is a sectional view, partly broken away, on the lines 3—3, Fig. 2.

This invention is adapted for use in connection with a tank or receptacle into which the water preferably is introduced at the bottom through a pipe having a vertical extension adjacent to the side or end of the

receptacle, the valve mechanism being desirably supported on said pipe a short distance above the top of the receptacle in the manner illustrated in Fig. 1 of my prior Patent No. 964,833 above referred to.

In practice the pipe 1 is vertically arranged as shown in said patent and leads to a cylindrical extension 2 of a valve casing 3 which is provided with two valve chambers 4 and 5 having respectively nipples or pipes 6 and 7 connected to cold and hot water reservoirs or other suitable supplies.

The casing members 2 and 3 desirably form an integral structure provided with seats in the valve chambers to receive suitable valves, there being removable heads 8 and 9 through which the valves may be introduced and fitted within said casing. The valves are desirably identical in form and for that reason it will be sufficient to describe the operating mechanism in respect to one only. The valve stem 10 is extended through a suitable stuffing box 11 in the wall or side of the casing and its outer end is bifurcated and pivotally attached by a bolt or pin 12 to the intermediate portion of a lever 13 which is fulcrumed upon a pin 14 at the end of a link 15 which in turn is pivotally mounted upon a pin 16 secured to ears 17 projecting from the side and end of the casing 3.

The lever 13 is provided with a handle 18 by means of which it may be lowered to open the valve the desired amount. In order to lock the valve in open position frictional gripping means are provided which will retain the valve in correct adjustment, and means are also provided whereby upon releasing the locking means the valve will be automatically closed. The preferred means shown herein comprises a rod or link 20 having a bifurcated end 21 connected by a pivot 22 to the lever 13 intermediate of its handle and its connection to the valve stem. The main portion of the link 20 is preferably square in cross section and passes through an apertured gripping member which desirably may be a locking dog 23 loosely fitted about said link and having a cylindrical or spherical portion 24 pivotally

and slidably mounted in a suitable recess 25 in a stand 26, which desirably may be secured to the portion 2 of the casing by screws 27 extending through flanges 28 into 5 suitable bosses 29 on said casing. The inner end of the dog 23 is provided with a tail or projection 30 normally depressed by a spiral spring 31 mounted in a recess in a boss 32 extending upwardly from the stand 10 26 and provided with a suitable screw 33 forming an abutment or seat for said spring. The opposite end of the dog 23 desirably is provided with a curved nose constituting a thumb piece 34 whereby upon depression 15 of said thumb piece the dog will be rotated upon its bearing so that its gripping action upon the stem of the link 20 will be released and the valve stem permitted to slide freely. The opposite end portion 35 of the link 20 20 is desirably made cylindrical in form and is provided with a collar 36 forming a seat for one end of a spiral spring 37 which is supported at its opposite end upon a lug 38 extending laterally from the lower end of the 25 casing 3.

By the construction above described it will be obvious that the handle 18 and lever 13 may be depressed to open the valve any desired amount and that when so depressed the dog 23 will grip the opposite sides of the stem, as illustrated in Fig. 2 and retain the same in the exact position to which it was adjusted, so that the amount of water discharged into a receptacle by 30 35 either the hot or the cold water pipe or both may be accurately regulated.

As before stated it is desirable that the valve or valves which may be opened to permit the entrance of the water into the 40 receptacle will be closed when the level of the water in the receptacle reaches a certain predetermined level, and to effect this purpose suitable means such as that illustrated in my prior Patent No. 964,833 may 45 be provided to raise a suitable rod 40 adapted to actuate releasing mechanism whereby the valves may be returned to closed position by the action of the spring 37 upon the lever controlling the valves.

50 The releasing mechanism may be of any suitable character such as that disclosed in the drawings herein in which the rod 40 is connected to the end of a lever 41 suitably pivoted in ears 42 projecting laterally from 55 the casing 2, said lever 41 having at its opposite end a detent 43 adapted to engage a hook 44 carried by a sliding releasing member. The hook 44 desirably may be provided with a lateral projection 45 adapted 60 to contact with a lug 46 projecting from the side of the casing 2 to limit the movement of the lever and maintain the same in such position that when the sliding member is moved downward its end will wipe over

the inclined end of the detent 43 and thereby 65 enable the hook to engage the detent. The sliding releasing member as illustrated herein comprises a plate 47 suitably mounted in ways formed in lateral extensions secured to or projecting from the casing 3 and desirably is provided at its lower end with an extension 48 having a cam surface 49 adapted to engage the under surface of the projections or tails 30 of both the dogs 23 and 70 rotate them about their sliding pivots to 75 releasing position. The end of the projection 48 is shaped to constitute the hook 44 heretofore described which is engaged by the detent 43 when the valve is opened to admit water to the receptacle. The upper 80 end of the releasing member 47 may be provided with a handle 50 by which it may be depressed to cause the hook 44 to engage the detent 43 of the releasing lever 41.

In order to maintain the slide in position 85 and to cause the same to be pressed normally upwardly to cause the release of the valve controlling member or members, the under face of the sliding member 47 is provided with a T-shaped downward extension 51, 90 one arm 52 of which is extended through an opening in a supporting flange 53, while the other arm 54 constitutes a core for a spiral spring 55 which is seated at its opposite end upon a flange 56 extending laterally from the casing 3. The spring 55 when in place, is under compression so that the slide is maintained normally at the upward limit of its movement, in which position the releasing cam 49 will engage the 100 tails 30 of the dogs 23, maintaining the dogs in such position that the rods 20 will slide freely through the openings in said dogs, thus permitting the valve to be held in closed position by the springs 37. 105

When the operator desires to introduce either hot or cold water or both into the receptacle he will first press down upon the handle 50 of the slide 47 forcing the latter downwardly until its hooked end 44 engages 110 the detent 43 of the lever 41. When the hook and detent are thus engaged the releasing cam 49 is removed from beneath the ends 30 of the dog 23 permitting said springs 31 to rock said dogs upon their sliding pivotal supports into gripping engagement with the rods 20. The operator may then depress the lever which controls the hot or the cold water pipe, or both. The depression of the 115 levers 13 is made against the tension of the springs 37 and the levers are locked in adjusted position by the frictional engagement of the dogs 23 with the rods 20 in the manner aforesaid. By reason of this frictional engagement the valves may be adjusted with 120 great accuracy so that the fluid introduced into the tank may be regulated to the desired 125 temperature.

When the liquid in the receptacle has reached the predetermined level the rod 40 will be raised, thereby rotating the lever 41 about its pivot and releasing the engagement 5 between its detent 43 and the hook 44 of the slide 47 and the cam surface 49 riding under the tails 30 of the dogs 23 will rock the latter in such a manner as to permit the free movement of the rods 20 through said dogs. 10 Upon being thus released the spring 37 will force the rods 20 upwardly raising the lever 13 and thereby raising and closing the valve automatically.

It is to be understood that the machine 15 closed herein constitutes one embodiment of my invention but that the invention may be included in other constructions and that various modifications may be made within the scope thereof.

Having thus described my invention what I claim as new and desire to secure by Letters Patent is:

1. The combination with a fluid receptacle having a plurality of inlet pipes, valves 25 to control the admission of fluid through said pipes, independent means for locking the respective valves in adjustably open position including spring actuated sliding members, spring actuated frictional gripping 30 means engaging said members and normally positioned to lock the same against sliding movement and releasing mechanism operable by the fluid when the same reaches a predetermined level to release said gripping members from frictional engagement with the 35 sliding members and to permit the closing of the valves.

2. The combination with a receptacle to contain fluid having a plurality of inlet 40 pipes containing valves to control the admission of fluid to said receptacle through said pipes, of independent means for locking the respective valves in open position comprising levers pivotally connected to the valve 45 stems, rods pivotally connected to said levers, frictional gripping means embracing said rods and normally positioned to lock the same, spring-pressed releasing mechanism adapted to disengage both said gripping 50 members, and means operable by the fluid in the receptacle to cause the action of the releasing means when the liquid reaches a predetermined level.

3. The combination with a receptacle to 55 contain fluid and a valve to control the admission of fluid thereto, of means for locking the valves in open position comprising a lever pivotally connected with the valve stem, a rod connected to said lever, a dog 60 pivotally and slidably movable relative to said rod and having gripping members, means for depressing the tail of said dog to cause the gripping members to engage said rod, spring actuating releasing mecha-

nism adapted to be manually positioned to 65 permit the dog to operatively engage the rod and means actuated by the liquid in the receptacle for disengaging the releasing mechanism to render the dog inoperative and permit the restoration of the valve to 70 closed position.

4. Valve closing means for the inlet to a fluid receptacle comprising a valve controlling means including a lever, a spring actuated rod connected to said lever and pivotally and slidably mounted gripping means 75 co-operating with said rod, means normally rocking said gripping means into engagement therewith, and means for manually releasing said gripping means.

5. Valve closing means for the inlet to a fluid receptacle comprising a valve controlling means including a lever, a spring actuated rod connected to said lever, a pivotally and slidably mounted gripping member co-operating with said rod and having means 80 normally rocking said gripping member into engagement therewith, and means for automatically moving said gripping member about its pivotal support to cause the release of said rod.

6. Valve closing means for fluid receptacles comprising a valve controlling means including a lever, a spring actuated rod connected to said lever, a pivotally and slidably mounted gripping member co-operating with said rod, means normally rocking said gripping member into engagement therewith, and means for automatically moving said gripping member about its 90 pivotal support to cause the release of said rod comprising a spring actuated releasing member having a cam surface adapted to engage the tail of said gripping member to rotate the same and means controlled by the 95 fluid in the receptacle to actuate said releasing means when the fluid reaches a predetermined level.

7. The combination with a fluid receptacle and a valve to control the admission 100 of fluid thereto, the means for locking the valve in open position comprising a lever pivotally connected to the valve stem, a spring pressed rod connected to said lever and normally tending to hold the valve in 105 closed position, a frictional gripping member embracing said rod and pivotally and slidably mounted thereon, means to cause the engagement of opposing surfaces thereof with said rod to thereby maintain said rod in 115 adjusted position against the tension of its spring, means for releasing said gripping mechanism comprising a spring actuated sliding member having a cam adapted to ride under a projection upon said gripping member and to move the same to inoperative 120 position, a hook carried by said sliding member, a lever having a detent adapted 125

to engage said hook, and means connected to said lever operable by the liquid in the tank upon reaching a predetermined level to disengage said hook and detent and cause 5 the actuation of the releasing mechanism to permit the closing of the valve.

In testimony whereof, I have signed my

name to this specification, in the presence of two subscribing witnesses.

THOMAS J. YATES.
